C. A. Parrott
BY Victor J. Evans

ATTORNEY

UNITED STATES PATENT OFFICE.

COLUMBUS A. PARROTT, OF TEXARKANA, TEXAS.

STARTER.

1,258,442.

Specification of Letters Patent.

Patented Mar. 5, 1918.

Application filed May 15, 1917. Serial No. 168,840.

To all whom it may concern:

Be it known that I, COLUMBUS A. PARROTT, a citizen of the United States, residing at Texarkana, in the county of Bowie and 5 State of Texas, have invented new and useful improvements in Starters, of which the following is a specification.

My invention relates to starters for internal combustion motors and has for its 10 primary object to provide a starter which will not transmit the occasional backward "kick" of the motor and result in injury to the operator.

A further object of my invention is to 15 provide means for locking the starter in an inoperative position to prevent unauthorized operation of the motor.

With these and other objects in view which will be hereinafter fully described 20 and particularly pointed out in the claims, the invention consists in the novel construction and arrangement of parts illustrated in the accompanying drawings, forming a part of this specification, in which:—

25 Figure 1 is a partial side elevation of an internal combustion motor to which a starter embodying my invention is attached.

Fig. 2 is a top plan view of the starter, the top of the casing having been removed 30 to more clearly show the operating parts thereon.

Fig. 3 is a similar view showing the clutch of the starter in engagement with a corresponding clutch on the crank shaft of the 35 motor preparatory to starting the motor.

Fig. 4 is a front elevation of the starter showing the separating shield in the position it assumes when the motor kicks back,

Fig. 5 is a similar view of the starter 40 showing the device locked to prevent unauthorized operation of the motor.

Like characters of reference indicate like parts in the various views.

In the drawings 1 designates generally 45 an internal combustion motor which is provided with a crank shaft 2, said crank shaft normally rotating in a clockwise direction as is the usual practice. The forward end of the crank shaft is provided with a laterally faced receding cam type clutch 3, the clutching faces of the clutch 3 facing in a counter-clockwise direction.

Mounted on the structure of the motor is 50 a frame 5 comprising a rear plate 6 and front plate 7, the edges of said front plate 7 being turned back to form the top, bot-

tom, and ends of the frame, the rear edges of said top, bottom and ends being turned outwardly to form flanges 8, and said flanges are secured to the rear plate 6 by means of 60 bolts 9. A shaft 10 is mounted for rotation and for longitudinal movement in a boss 11, formed on the rear plate 7 and is disposed in axial alinement with the crank shaft 2. The rear end of the shaft 10 is provided 65 with a laterally faced receding cam type clutch 12, the clutching faces 13 of which are faced in a clockwise direction, and are adapted to engage the clutching faces 4, when the shaft 10 is moved inwardly to 70 rotate the crank shaft 2 in a clockwise direction. An extension 14 is formed upon the rear surface of the plate 6 and extends rearwardly therefrom and has a bearing 15 engaging the shaft 10 immediately in front 75 of the clutch 12. A coiled compression spring 16 encircles said shaft 10 just in front of the bearing 15, and has its rear end abutting the same, and has its front end abutting a collar 17 mounted upon the 80 shaft 10. Said spring 16 serves to normally retain the shaft 10 in its outer position with the clutch 12 disengaged from the clutch 3. A shaft 18 is mounted for rotation and for longitudinal movement in a 85 boss 19 of the front plate 7. Said shaft 18 is preferably disposed in axial alinement with the shaft 10, and has a gear 20 mounted on the inner end thereof, said gear lying just in back of the front plate 7 and abutting 90 the outer face of a gear 21 mounted upon the outer end of the shaft 10. A crank- 95 ing handle 22 is mounted upon the outer end of the shaft 18. A shaft 23 is mounted in a pair of slots 24 formed in respective plates 6 and 7, said slots being disposed radially respecting the shaft 10. A yoke 25 has respective arms thereon secured to the shaft 23 adjacent respective slots 24, and a rod 26 has its one end secured to the 100 transverse portion of the yoke and extends through the hole 27 formed in the end member of the frame 5. A gear 28 is rotatably mounted upon the shaft 23 between the arms of the yoke 25, and is adapted, when the 105 yoke is moved toward the shaft 10, to mesh with the gears 20 and 21. A coiled compression spring 29 encircles the rod 26 and abuts the yoke 25 and the end of the frame with its respective ends whereby said gear 110 28 is normally held in meshed engagement with the gears 20 and 21. The ends of the

slots 24, which lie nearest the shafts 10 and 18 serve to prevent spring 29 from meshing the gears too tight. A separating shield 30 is mounted for pivotal movement upon the shaft 23 by means of arms 31 extending downwardly on either side of the gear 28 engaging said shaft with journals between the respective arms of the yoke 25 and the gear 28. A lug 32 is formed upon the separating shield 30, and a pair of stops 33 are formed on the rear plate 6 and are disposed in the path of movement of the lug 32 to limit the movement of the shield 30 in both directions. A pawl 33 is pivotally mounted upon the shield 30 and is adapted to engage the teeth of the gear 28, and is so disposed that when the gear 28 rotates in a clockwise direction the gear will rotate the shield through the medium of the pawl. A flat spring 34 has its one end secured upon the shield 30 and engages the pawl 33 with its other end and hold the pawl in engagement with the teeth of the gear 28. A tongue 35 is formed upon the shield 30 and is adapted to pass between the gear 28 and the gears 20 and 21 to support the same against the influence of the spring 29 when the gear 28 is rotated in a clockwise direction and the shield is moved thereby through the medium of the pawl 33, as hereinbefore described. A coil spring 35' has its one end connected to the shield 30 and its other end connected to the rear plate 6, and serves to normally position the tongue of the shield out of engagement with the gear, said lug 32 to respective stop 33 serving to prevent said spring from moving the shield too far.

It will be noted from the above description, that the shield 30 is held in an operative position when the gears 20 and 21 are rotated in a clockwise direction and the gear 28 rotates in a counter-clockwise direction. However, when the gears 20 and 21 rotate in a counter-clockwise direction and the gear 28 rotates in a clockwise direction the pawl 33 engages the teeth of the gear 28 and the shield is moved therewith in a clockwise direction whereby the tongue 35 is driven in between the gear 28 and the gears 20 and 21, and the gear 28 is moved out of engagement with the gears 20 and 21 against the influence of the spring 29. As soon as the gears are separated the gear 28 stops rotating the gears 20 and 21 slip over the surface of the tongue 35, the friction of said gears 20 and 21 serving to hold the lug 32 against the respective stop 33, against the influence of spring 35'. When the mechanism is in this position the gears 20 and 21 are out of driving connection with each other, see Fig. 4. Thus it will be seen that while the gears 20 and 21 are rotated in a clockwise direction a driving connection may be maintained therebetween, whereas, when the gears 20 and 21 are ro-

tated in a counter-clockwise direction the shield 30 breaks the driving connection between the gears 20 and 21, and prevents the shaft 10 from rotating the shaft 18 in a counter-clockwise direction, as would be the case if the motor 1 kicked back while it was being cranked.

The rod 26 extends some distance beyond the hole 27 and has a pivot stud 36 mounted near the outer end thereof. A cam lever 37 is pivoted upon said stud at a point intermediate its ends and has a cam surface 38 formed at one end thereof, which engages the outer surface of the frame adjacent the hole 7 when the cam lever is actuated to withdraw the rod out of the hole. A transverse hole 29 is formed in the rod 27 at the outer end thereof, and a hole 40 is formed in the cam lever 37 which is adapted to register with said hole 39 when the cam lever is positioned to hold said rod in its retracted position. When in this position the hasp 41 of an ordinary padlock 42 may be inserted in said holes to lock the rod in its retracted position. When the rod 27 is in a retracted position the gear 28 is withdrawn from engagement with the gears 20 and 21, the gears 20 and 21 are out of driving connection with each other. Thus it will be seen, that by locking the rod 27 in its retracted position the starter may be rendered inoperative to prevent unauthorized operation of the motor.

Having thus fully described my invention, I claim:

100

1. In a device of the character described, the combination with a gear mounted for rotation, a second gear mounted for rotation and lateral movement and adapted to mesh with said first mentioned gear, a separating shield adapted to pass between said gears and to move said second gear out of mesh with said first mentioned gear, and a pawl mounted on said shield and engaging one of said gears to move said shield between said gears when said gears are rotated in one direction.

115 2. In a device of the character described, the combination with a gear mounted for rotation, a second gear mounted for rotation and lateral movement and adapted to mesh with said first mentioned gear, a spring adapted to normally hold said second gear in meshed engagement with said first mentioned gear, a separating shield adapted to pass between said gears and to move said second gear out of mesh with said first mentioned gear, a pawl mounted on said shield and engaging one of said gears to move said shield between said gears when said gears are rotated in one direction, a lug on said shield, a pair of stationary stops disposed in the path of said lugs to limit the move- 130

8

ment of said shield in either direction, and a spring adapted to normally hold said shield out of engagement with said gears.

3. In a device of the character described, 5 the combination with a frame having a hole at one end thereof, a gear mounted for rotation in said frame, a shaft for said gear, a second gear mounted for rotation in said frame and adapted to mesh with said first 10 mentioned gear, a yoke mounted on said shaft, a rod mounted on said yoke and having its outer end extending through said hole and having a hole formed thereon near the outer end thereof, a compression spring 15 encircling said rod and abutting said yoke and said frame with its opposite end, a transverse pivot stud mounted on said rod at a point intermediate the ends of said rod and disposed exteriorly of said frame, and 20 a cam lever pivoted on said pivot stud at a point intermediate the ends thereof and adapted to engage said frame with one of its ends to retract said coil from engagement with said first mentioned gear, and having 25 a hole therein adapted to register with said hole in said rod whereby the hasp of an ordinary padlock may be inserted into said second and third mentioned holes to lock said second gear in a retracted position. 30 4. In a device of the character described, the combination with a frame having a hole at one end thereof, a gear mounted for rotation in said frame, a shaft mounted for lateral movement in said frame, a second 35 gear mounted for rotation on said shaft and adapted to mesh with said first mentioned gear, a yoke mounted on said shaft, a rod mounted on said yoke and having its outer end extending through said hole and having 40 a hole formed therein near the outer end thereof, a compression spring encircling said rod and abutting said yoke and said frame with its opposite ends, a separating shield adapted to pass between said gears and to move said second gear out of mesh with said first mentioned gear, a pawl pivotally mounted on said shield and engaging one of said gears to move said shield between said gears when said gears are rotated in one direction, a lug on said shield, a pair of stationary stops disposed in a path 45 of said lug to limit the movement of said shield in either direction, a second spring adapted to normally hold said shield out of engagement with said gears, a transverse pivot stud mounted on said rod at a point intermediate the ends of said rod and disposed exteriorly of said frame, and a cam lever pivoted on said pivot stud at a point intermediate the ends thereof and adapted to engage said frame with one of its ends to retract said second gear from engagement with said first mentioned gear and having a hole therein adapted to register with said hole in said rod whereby the hasp of an ordinary padlock may be inserted into said 50 second and third mentioned holes to lock said second gear in a retracted position. 55 6. In a device of the character described, the combination with a gear mounted for rotation and for longitudinal movement, a 60 spring adapted to retain said gear in its outer position, a second gear mounted for rotation and for lateral movement and adapted to mesh with said first mentioned gear, a third gear mounted for rotation and for longitudinal movement and adapted to mesh with said second gear and adapted to abut the inner surface of said first mentioned gear, and a second spring adapted to normally hold said second gear in meshed relation with said first mentioned gear and said third gear. 65 7. In a device of the character described, the combination with a gear mounted for rotation and for longitudinal movement, a 70 spring adapted to retain said gear in its outer position, a second gear mounted for rotation and for lateral movement and adapted to mesh with said first mentioned gear, a third gear mounted for rotation and for longitudinal movement and adapted to mesh with said second gear and adapted to abut the inner surface of said first mentioned gear.

5. In a device of the character described, 65 the combination with a frame having a hole

gagement with said first mentioned gear and said third gear, a separating shield adapted to pass between said gears and to move said second gear out of mesh with said first mentioned gear, and a pawl pivotally mounted on said shield and engaging one of said gears to move said shield between said gears when said gears are rotated in one direction.

- 10 8. In a device of the character described, the combination with a gear mounted for rotation and for longitudinal movement, a spring adapted to retain said gear in its outer position, a second gear mounted for 15 rotation and for lateral movement and adapted to mesh with said first mentioned gear, a third gear mounted for rotation and for longitudinal movement and adapted to mesh with said second gear and adapted to 20 abut the inner surface of said first mentioned gear, a second spring adapted to normally hold said second gear in meshed engagement with said first mentioned gear and said third gear, a separating shield 25 adapted to pass between said gears and to move said second gear out of mesh with said first mentioned gear, a pawl pivotally mounted on said shield and engaging one of said gears to move said shield between 30 said gears when said gears are rotated in one direction, a lug on said shield, a pair of stationary stops disposed in the path of said lug to limit the movement of said shield in either direction, and a second spring 35 adapted to normally hold said shield out of engagement with said gear.

9. In a device of the character described, the combination with a gear mounted for rotation and for longitudinal movement, a 40 spring adapted to retain said gear in its outer position, a second gear mounted for rotation and for lateral movement in said frame and adapted to mesh with said first mentioned gear, a third gear mounted for 45 rotation and for longitudinal movement and adapted to mesh with said second gear and adapted to abut the inner surface of said

first mentioned gear, a second spring adapted to normally hold said second gear in meshed engagement with said first mentioned gear and said third gear, and means for retracting said second gear from engagement with said first mentioned gear and said third gear, said means being adapted to be locked when in its retracting position.

10. In a device of the character described, the combination with a frame having a hole at one end thereof, of a gear mounted for rotation and for longitudinal movement in 60 said frame, a spring adapted to retain said gear in its outer position, a shaft mounted for lateral movement in said frame, a second gear mounted for rotation on said shaft and adapted to mesh with said first mentioned gear, a yoke mounted on said shaft, a rod mounted on said yoke and having its outer end extending through said hole and having a hole formed therein near the outer end thereof, a compression spring encircling 70 said rod and abutting said yoke and said frame with its opposite ends, a transverse pivot stud mounted on said rod at a point intermediate the ends of said rod and disposed exteriorly of said frame, a cam lever 75 pivoted on said pivot stud at a point intermediate the ends thereof and adapted to engage said frame with one of its ends to retract said second gear from engagement with said first mentioned gear and having 80 a hole therein adapted to register with a hole in said rod whereby the hasp of an ordinary padlock may be inserted into said second and third mentioned holes to lock said second gear in a retracted position, and a 85 third gear mounted for rotation and for longitudinal movement and adapted to mesh with said second gear and adapted to abut the inner surface of said first mentioned gear. 90

In testimony whereof I affix my signature.

COLUMBUS A. PARROTT.
